DESIGN FOR A BABY'S TRAY

John P. Bourdius, New York, N. Y.

Application March 20, 1945, Serial No. 118,593

Term of patent 7 years

(Cl. D58—4)

To all whom it may concern:

Be it known that I, John P. Bourdius, a citizen of the United States, residing at New York, in the county and State of New York, have invented a new, original, and ornamental Design for a Baby's Tray, of which the following is a specification, reference being had to the accompanying drawing, forming part thereof.

Fig. 1 is a perspective view of a baby's tray embodying my new design; and

Fig. 2 is a top plan view of the same.

I claim:

The ornamental design for a baby's tray, substantially as shown.

JOHN P. BOURDIUS.
